UNITED STATES PATENT OFFICE.

HENRY GOEDDERTZ, OF DENVER, COLORADO, ASSIGNOR OF ONE-HALF TO CLARK RIDER, OF DENVER, COLORADO.

CANDLE-HOLDER.

1,175,057.

Specification of Letters Patent. Patented Mar. 14, 1916.

Application filed October 20, 1914. Serial No. 867,572.

To all whom it may concern:

Be it known that I, HENRY GOEDDERTZ, a citizen of the United States, residing in the city and county of Denver and State of Colorado, have invented certain new and useful Improvements in Candle-Holders; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to improvements in candle-holders, my object being to provide a device of this class adapted to conceal the candle at all times during the burning operation, and prevent the melted material from 20 running down on the outside of the candle, as is usual where the candle is burned or used in an exposed condition.

In the preferred form of construction, a base or tray in imitation of the usual base 25 or tray of a candle stick, may be secured to the tubular shield of the candle, and move downwardly therewith as the candle burns away, this tray or base giving additional 30 weight to the tube to cause the same to move downwardly, whereby the shoulder or stop at the upper extremity of the tubular shield will follow the upper end of the candle and maintain itself in contact therewith without any tendency to stick or bind.

35 Having briefly outlined my improved construction, I will proceed to describe the same in detail, reference being made to the accompanying drawing, in which is illustrated an embodiment thereof.

40 In this drawing,—Figure 1 is a sectional view of my improved candle holder, supported by a pedestal, the base of which is broken away. In this view, the candle is shown in position within the holder and 45 lighted as when in regular use. Fig. 2 is a sectional detail view of the pedestal or base, carrying the rod which is adapted to act on the lower extremity of the candle. In this view, the other features are omitted. Fig. 3 50 is a sectional detail view of the tubular shield with the tray or base attached. Fig. 4 is an elevation of the construction shown in Fig. 1. Fig. 5 is a sectional fragmentary detail view of the upper extremity of the 55 device showing the candle practically con-

sumed, or burned so closely to its lower extremity that its outer shield or tube can no longer move downwardly. Fig. 6 is a sectional detail view showing the modified form of construction. Fig. 7 is a similar view 60 showing the candle partly consumed.

The same reference characters indicate the same parts in all the views.

Referring first to Figs. 1 to 5, inclusive, let the numeral 5 designate a vertically movable tubular shield which, when assembled in position for use, is in telescopic relation with an interior rod 6, which is secured as shown at 7, to a suitable stationary support consisting of an outer tube or casing 8, in 70 the lower portion of which is secured a plug 9, the tube 8 being mounted in a perforation formed in the pedestal or standard 10 and secured in operative relation therewith by means of a set screw 12. By virtue of this 75 construction and arrangement when the parts are assembled, as shown in Figs. 1 and 4, the tubular shield 5 extends downwardly 80 into the outer tube or casing 8, and is vertically movable therein. The rod 6 extends above the top of the casing 8 as does the shield 5. As illustrated in the drawing, the tubular shield 5 is provided with a base or tray 13, the same being attached to the tube 5 at a suitable distance below the upper 85 extremity of the tube, to give the tube and tray the general appearance of an ordinary candle stick, the upper portion of the tube being white in imitation of a candle when exposed. Within the upper portion of the 90 shield 5, is located a candle 14, whose lower end rests upon the upper extremity of the rod 6. In this event, the lower extremity of the shield 5 is arranged at a suitable distance above the plug 9 which forms the stop 95 for the said tube by engaging the lower extremity thereof.

In using my improvement, the candle to be used is inserted into the tube from the lower extremity thereof, which is open for the purpose. The tube is then introduced into the casing 8, which is open at the top and moved downwardly therein until the upper extremity of the rod 6 shoves the upper extremity of the candle 9 against a stop 100 or interior shoulder 15, which is secured at the top of the tube. The candle is then lighted and as it burns away, the weight of the tube 5 and the tray or base 13 attached thereto, causes the tube to move downwardly 105 110

as fast as the candle burns. During this operation, the conditions are as illustrated in Fig. 5, since there will be a small quantity 16 of melted material in the upper part 5 of the shield and surrounded by the stop 15 which, as shown in the drawing, consists of a wire ring which is soldered or otherwise secured within the upper extremity of the tube. This melted accumulation which 10 is in contact with the wick 17 of the candle, passes upwardly and is consumed as the candle burns. My improvement is therefore important from the standpoint of economy since no part of the candle is wasted where 15 my improvement is employed. Furthermore, there is no opportunity for the melted material to run down on the outside of the candle or upon the outside of the tube or shield in which the candle is located.

20 The upper part 18 of the tubular shield, above the base or tray 13, is provided with an exterior circumferential rib 19, which gives it the appearance of an ordinary candle stick, the tubular part 20 below the rib 25 resembling a socket adapted to receive the upper part 21 of the tube, the latter itself having the appearance of an exposed candle, and being of the same color as the candle.

When the candle has burned to the desired 30 limit, or to the maximum degree, only a small portion of it will remain in the upper extremity of its tubular shield, and the latter may be removed from the pedestal or other support, and after the remnant of the 35 candle has been removed, a new candle may be substituted therefor, after which the operation will continue as before.

In the form of construction shown in 40 Figs. 6 and 7, a tray 22 provided with a handle 23 is centrally equipped with an upwardly projecting tubular casing 24. Within this casing is located an upwardly projecting rod 25 whose upper extremity engages the lower end of the candle 14. The 45 portion of the candle which projects above the top of the tube 24 is surrounded and concealed by a tubular casing 26, whose lower extremity protrudes into the upper part of the stationary casing 24, when the 50 candle is first introduced. As the candle burns away, the tubular casing 26 moves downwardly to a corresponding degree, while the rod 25 maintains the candle in engagement with the shoulder or stop 15 55 at the upper extremity of the tube 26. The position of the different parts after the

candle is nearly consumed, is illustrated in Fig. 7.

The construction illustrated in Figs. 6 and 7 shows my improvement utilized to 60 take the place of an ordinary candle stick, which is portable or adapted to be moved with the same facility as candle sticks of ordinary construction. At the same time, the melted material of which the candle is 65 composed, is prevented from running down on the outside of the candle, as is the case where candles are exposed in ordinary candle sticks, as heretofore described.

From the foregoing description, the use 70 and operation of my improvement will be readily understood and need not be further described in detail.

Having thus described my invention, what I claim is,—

75 1. A candle holder comprising a relatively stationary casing, a rod secured within the casing and of such size as to leave an annular space therearound, a tube adapted to slide freely within the said space between 80 the rod and the casing, a ring secured to the inner periphery of the tube at its upper extremity and adapted to engage the outer portion of the upper extremity of the candle, whereby a shallow recess whose 85 width is approximately equal to the thickness of the candle is formed between the flat upper end of the candle and the top of the tube during the burning of the candle, the tube being of such length that its lower extremity will enter the upper end of the casing when the stop at the upper end of the tube is a candle-length above the upper end of the rod, the tube having a tray secured thereto intermediate its extremities and 90 adapted to engage the top of the casing and limit the downward movement of the tube within the casing, substantially as described.

95 2. A candle holder comprising a tube, a ring secured to the interior of the tube at 100 its upper extremity and adapted to engage the top of the candle directly adjacent the periphery of the latter, and a casing at the bottom of the holder adapted to receive said tube as the candle burns away.

105 In testimony whereof I affix my signature in presence of two witnesses.

HENRY GOEDDERTZ.
